UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

BINDING-TERMINAL.

1,282,525.

Specification of Letters Patent. Patented Oct. 22, 1918.

Application filed February 29, 1916. Serial No. 81,101.

To all whom it may concern:

Be it known that I, REUBEN B. BENJAMIN, a citizen of the United States, residing at Chicago, in the county of Cook and State 5 of Illinois, have invented new and useful Improvements in Binding-Terminals, of which the following is a full, clear, concise, and exact description, reference being had to the accompanying drawing, forming a part of 10 this specification.

My invention relates to binding terminals.

Among the objects of my invention is to provide a binding terminal by means of which the wiring can be quickly accomplished and which will securely hold the wire, and which will be simple in construction and cheap to manufacture.

In the drawings, in which I have shown several embodiments of my invention—

20 Figure 1 is a side elevation of a receptacle;

Fig. 2 is an axial section of this receptacle;

Fig. 3 is a view of the open end of the receptacle of Fig. 1;

Fig. 4 is a view of the closed end of the 25 receptacle;

Fig. 5 is a section on the line 5—5 of Fig. 2;

Fig. 6 is a section on the line 6—6 of Fig. 4;

30 Fig. 7 is a plan view of the binding terminal for the center contact;

Fig. 8 is a side elevation of the binding terminal shown in Fig. 7;

Fig. 9 is a plan view of the center contact;

35 Fig. 10 is a side elevation of the center contact;

Fig. 11 is a side elevation of another form of receptacle;

Fig. 12 is a section on the line 12—12 of 40 Fig. 11;

Fig. 13 is a section on the line 13—13 of Fig. 12;

Fig. 14 is a section on the line 14—14 of Fig. 12 looking up;

45 Fig. 15 is a view of the open end of the receptacle;

Fig. 16 is a side elevation of a switch provided with my improved binding terminal;

50 Fig. 17 is a section on the line 17—17 of Fig. 16;

Fig. 18 is a sectional view showing one form of binding terminal;

Fig. 19 is a plan view of the binding plate 55 of Fig. 18; and

Figs. 20, 21 and 22 are sectional views of other forms of binding terminals.

Referring now to the drawings in detail and first to Figs. 1 to 10, inclusive, the improved binding terminal is here shown in 60 connection with a receptacle comprising an insulating base 10, shell and center contacts 11 and 12, supported by the base, and binding terminals 13 and 14 for the shell and center contacts, respectively. The base 10 65 has openings 15 and 16 on opposite sides for the entrance of the ends of the wires. The shell contact comprises a threaded portion 17 and a flange portion 18 which is held on the base 10 by means of nuts 19 and screws 20. The center contact comprises a spring contact portion 21 and a base portion 22 which is secured to the insulating base by means of an eyelet 23. The binding terminal 13 comprises a binding plate 24 and a binding screw 25 which is threaded into a plate 26 secured on the insulating base by means of an eyelet 27. The binding plate 24 comprises a portion 28 having a slot 29 therein through which the screw 25 extends, an inclined portion 30 for engagement with the conical under surface of the head of the screw 25 and a portion 31 for retaining the end of the wire in place and holding it against the binding screw and a portion 32 80 through which the eyelet 27 extends to secure the binding plate in place. The screw 25 has a flat head 33 having a conical under surface 34 for engagement with the inclined portion 30. The flange portion 18 of the shell contact is slotted at 35 to accommodate the screw 25 and to allow movement of this screw. The binding terminal 14 comprises a binding plate 36 and a binding screw 37 which is threaded into a plate 38 of conducting material secured to the insulating base by means of an eyelet 23. The binding plate 36 is substantially the same as the binding plate 24 except that it has an extension 39 through which the eyelet 23 extends 100 to hold the binding plate in place.

In wiring the device the ends of the wires 40 are inserted through the openings 15 and 16 beneath the heads of the screws 25 and 37 and these screws are then tightened down on the ends of the wires. As each screw is tightened down the conical under surface 34 of its head engages the inclined portion 30 forming a support for the screw against the strain on the screw head due to the reaction 110

of the end of the wire against the head and the inclined portion 30 also acts as a wedge to force the screw over against the end of the wire to clamp the wire between the head 5 of the screw and the portions 28 and 31, the slot 29 in the portion 28 permitting this action of the screw. The engagement of the conical surface 34 of the screw head with the end of the wire will also force the latter down 10 into the slot 29 as indicated in Fig. 18, forming a kink in the wire which materially aids in securely holding it.

In Figs. 11 to 15, inclusive, the binding terminal is shown in connection with a different form of receptacle in which the ends of the wires are inserted through openings in the ends of the receptacle instead of through openings in the sides. The receptacle shown in these figures comprises an insulating base 41, a shell contact 42 supported by the base, a combined binding terminal and retaining member 43 for the shell contact and a combined center contact and binding terminal 44. The insulating base has 15 openings 45 and 46 in its ends for the ends of the wires and openings 47 and 48 on opposite sides affording access to the binding screws. The shell contact 42 has a threaded portion 49 and a flange portion 50 for securing it to the insulating base. The combined center contact and binding terminal member 44 comprises a spring contact portion 51, a base portion 52 secured to the insulating base by means of an eyelet 53 and a binding 20 terminal portion comprising a portion 54 having a slot 55 through which the binding screw extends, an inclined portion 56 for engagement with the conical under surface of the head of the binding screw, and a portion 25 57 for retaining the end of the wire and holding it against the binding screw 58.

The combined binding terminal and retaining member 43 comprises a yoke portion 59 which engages the flange portion 50 and 25 is held in place on the insulating base by means of screws 60, and a binding terminal portion 61 which is substantially like the binding terminal portion 44 just described. In this form the ends of the wires are in 30 inserted through the openings 45 and 46 and a screw driver is inserted through the openings 47 and 48 to tighten the screws down on the ends of the wires, the action of the binding terminals being the same as in the form 35 shown in Figs. 1 to 10.

In Figs. 15 and 16 the binding terminal is shown in connection with a switch 62 comprising a sheet metal casing 63, an insulating base 64 within the casing 63, a switch button 65 for operating the switch and a combined binding terminal and conducting member 66 supported on the insulating base. The base 64 is recessed at 67 to accommodate the member 66. The member 66 comprises a 40 base portion 68 secured to the insulating

base by means of screws 69 and a binding terminal portion 70 which is substantially the same as the binding terminal portion 61 just described. In wiring this device the casing 63 is slipped off of the insulating base 70 and the wire is inserted beneath the head of the screw which is then tightened down, the action of the binding terminal being the same as in the previously described form.

Figs. 18 and 19 illustrate one form of 75 binding plate and screw. In this form the binding plate 71 has a portion 72 slotted at 72^a to accommodate the binding screw having an inclined portion 73 for engagement with the conical under surface of the binding screw and an up-turned portion 74 for holding the end of the wire in place.

In Fig. 20 the binding plate is the same as in Figs. 18 and 19, but a button head screw 75^a substituted for the flat head screw.

In Fig. 21 a flat head screw is used but the binding plate 76 differs from the binding plate 71 in that the up-standing portion 77 does not engage the conical under surface of the head of the screw but engages the edge 90 of the head. In both of the forms shown in Figs. 20 and 21, however, it will be noted that the head of the screw is supported against the reaction of the wire against it by means of a portion struck up from the binding plate and engaging the head of the screw.

In Fig. 22 the binding plate is the same as in the form shown in Fig. 21 but a button head screw is substituted for the flat head screw. In all of the forms shown in Figs. 18 to 22 it will be noted that the end of the wire is forced down into the slot in the binding plate by the head of the binding screw forming a kink in the wire which assists materially in securely holding it.

Having thus described my invention what I claim as new and desire to secure by Letters Patent is:

1. A binding terminal comprising a binding plate and a binding screw, said binding plate having a portion having an opening through which said screw extends, said screw having a head having a conical under surface, and said binding plate having an inclined portion for engaging said conical surface for supporting the screw head, said head and plate having cooperating portions for clamping a conductor therebetween.

2. A binding terminal comprising a binding plate and a binding screw, said binding plate having a portion having an opening through which said screw extends, said screw having a head having a conical under surface, and said binding plate having an inclined portion for engaging said conical surface for supporting the screw head, said opening being elongated in a direction to permit said screw to be wedged over against the wire by said engagement.

3. A binding terminal comprising a binding plate and a binding screw, said binding plate having a portion having an opening through which said screw extends, said screw 5 having a head having a conical under surface, and said binding plate having an inclined portion for engaging said conical surface for supporting the screw head, and having an up-turned portion on the opposite 10 side of said screw from said inclined portion for holding the wire in engagement with said screw.

4. A binding terminal comprising a binding plate and a binding screw, said binding plate having a portion having an opening through which said screw extends, said screw 15 having a head having a conical under surface, said opening being elongated to permit the wire to be bent thereinto by said screw 20 head, said head and plate having co-operating portions for clamping a conductor therebetween.

5. A binding terminal comprising a binding plate and a binding screw, said binding plate having a portion having an opening through which said screw extends, said screw 25 having a head, said opening being elongated to permit the wire to be bent thereinto by said screw head, said head and plate having 30 co-operating portions for clamping a conductor therebetween.

6. A binding terminal comprising a binding plate and a binding screw, said binding plate having a portion having an opening

through which said screw extends, said screw 35 having a head, said opening being elongated to permit the wire to be bent thereinto by said screw head, said binding plate having an upturned portion engaging said screw head on the side opposite the wire for supporting said head. 40

7. A binding terminal comprising a binding plate member, a screw having a head having a conical undersurface between which and said binding plate member the conductor 45 may be clamped, whereby said conductor will react laterally against said head, said plate member having an inclined portion for engaging said conical surface on the side opposite that upon which said head engages 50 the conductor for supporting said screw head against the reaction of said conductor.

8. A binding terminal comprising a binding plate member, a screw having a head having a conical under surface between 55 which and said binding plate member the conductor may be clamped, whereby said conductor will react laterally against said head and a member having an inclined portion for engaging said conical surface on the 60 opposite side of which said head engages the conductor for supporting said screw head against the reaction of said conductor, and for forcing it over against said conductor.

In witness whereof, I have hereunto subscribed my name.

REUBEN B. BENJAMIN.
